MOISTUREPROOFING DEVICE

Morris A. Shiro, Elberon, N. J., assignor to the
United States of America, as represented by the
Secretary of War

Application January 20, 1944, Serial No. 519,013

1 Claim. (Cl. 220—85)

(Granted under the act of March 3, 1883, as
amended April 30, 1928; 370 O. G. 757)

1

The invention described herein may be manufactured and used by or for the Government for governmental purposes, without the payment to me of any royalty thereon.

My invention relates to means for moisture proofing closed compartments and more particularly to the use of a collapsible member to prevent the ingress and egress of air to a sealed compartment.

The necessity for moisture proofing scientific apparatus is well known. One solution to this problem lies in placing apparatus in sealed compartments. A survey of the state of the art reveals that it is difficult to hermetically seal a compartment so as to eliminate completely all minute openings. It has been found that when the air in a sealed compartment becomes heated, the air expands and passes out through the minute openings resulting from improper sealing. Then, when the internal air cools, a partial vacuum is formed within the compartment and external air containing moisture will enter the compartment through the minute openings. This moisture condenses within the closed compartment and results in oxidation of any apparatus contained therein.

It is an object of my invention to furnish a means for effectively sealing compartments.

It is a further object of my invention to provide a collapsible apparatus, which apparatus shall act in conjunction with a compartment to effectively seal the compartment.

It is a further object of my invention to provide an apparatus which shall compensate for the expansion or contraction of the air within a sealed compartment so that no air will pass in or out through any small openings that may remain subsequent to the sealing of the compartment.

I have solved the problem of effectively sealing closed compartments by introducing into the compartment an airtight collapsible member, which member is open at one end. This open end is positioned over an aperture in a wall of the compartment, and the junction is sealed airtight. Suitable means are provided for mounting the collapsible member, for sealing the junction, and for protecting the collapsible member against injury.

My invention thus discloses an inexpensive and effective apparatus by means of which a closed compartment may be completely insulated against the passage of air through any minute openings that may remain after the compartment has been sealed. The advantage of the invention will be

readily seen in connection with the necessity for sealing radio sets and components in moisture proof containers.

By the use of my invention, the air in the compartment, when it becomes heated and expands, will spend itself in collapsing the collapsible member, rather than in forcing its way through any minute openings that may exist. Thus there will be a movement of air within the compartment, but there will be no passage of air from the inside of the compartment to the outside thereof.

Heretofore this expansion of air has resulted in the passage of air through minute openings in the compartment to the outside thereof. Thus when the compartment cooled, a partial vacuum has formed within the compartment, and external air containing moisture has entered the compartment. The presence of this moisture results in rapid deterioration of the apparatus within the compartment.

For a better understanding of my invention, together with other and further objects, reference is had to the following description, taken in connection with the accompanying drawing:

25 Figure 1 is a perspective view of my invention, in which the compartment is partially cut away to show the elements of my invention.

Figure 2 is a cross-sectional view of my invention taken through line 2, 2 of Figure 1.

30 Referring to the figures in which like numbers refer to like elements, 1 represents a hermetically sealed compartment that has been provided with an aperture. An airtight collapsible member 4, which is closed at one end, opens externally to the compartment through the aperture.

Guard 6, the lower ends of which are drilled to receive bolts, is placed around collapsible member 4 for protection and support. Annular frame 2, in which is positioned grill 3, is placed on the outer surface of compartment 1 around and over the aperture. Annular washer 5 is placed between collapsible member 4 and guard 6.

In the embodiment shown, the arms of the guard 6 are radially 45° apart. Thus, the frame 2, collapsible member 4, annular washer 5, and the area immediately surrounding the aperture in compartment 1 are provided with holes 45° apart to provide for the introduction of bolts or other connecting means.

In assembly, annular frame 2, carrying grill 3, is placed over the circular aperture in compartment 1. A series of bolts are then inserted through the annular frame 2 and the wall of the compartment 1 to extend into the compartment.

Collapsible member 4 is then introduced onto the bolts. Annular washer 5 is then introduced, the purpose of which is to hold element 4 tightly against element 1 so that there will be no passage of air at this junction. Guard 6 is then introduced onto the bolts and the nuts are then placed on the bolts and drawn tight, thus holding the entire assembly in place.

Collapsible member 4, which, in the preferred embodiment of my invention, is shown to be a pliable airtight rubber sack, will be in its normal state distended. When the air in the compartment expands, the increased pressure will expand itself in collapsing the collapsible member rather than in escaping through any small openings that may exist in the sealed compartment. The collapse of the collapsible member 4 in effect results in an increase of the cubic measurement of the compartment when the air becomes heated and collapses the collapsible member, resulting in a constant air pressure. Since the air pressure remains constant there is no passage of air through minute openings to the exterior of the compartment.

When the air in the compartment 1 contracts upon cooling, the external air will enter through the aperture in the compartment and expand the sack 4 rather than enter through any small opening in the compartment. Thus the movement of air due to alternate expansion and contraction will operate solely upon the airtight collapsible member 4 and there will be no passage of air from and into the sealed compartment 1.

Although I have shown and described certain specific embodiments of my invention, I am fully aware that many modifications are possible. My invention, therefore, is not to be restricted except insofar as is necessitated by the prior art and by the spirit of the appended claim.

I claim:

A pressure equalizing device comprising an enclosed compartment, an aperture through a wall of said compartment, a substantially flat annular frame disposed about said aperture and outside said wall, a perforated grill sustained by said frame and extending across said aperture, the frame and grill being substantially flush with the exterior of said wall, a flexible sack, an opening in said sack, said sack being disposed within said compartment and said opening in said sack being in register with said aperture and the mouth of said opening abutting the inner surface of said wall, an annular washer encircling said sack, the mouth of the sack being between the wall and said washer, a perforated guard surrounding said sack, an opening in said guard, said opening in said guard abutting said washer, fastenings extending through and securing the frame, the sack, the washer and the guard to the wall of the compartment and pressing the mouth of the sack between the wall and the washer to form a tight seal between the mouth of the sack and the wall.

MORRIS A. SHIRO.
